UNITED STATES PATENT OFFICE

2,491,579

ELECTRIC RESISTANCE FURNACE

Frank F. Poland, Rome, N. Y., assignor to Revere Copper and Brass Incorporated, Rome, N. Y., a corporation of Maryland

Original application May 20, 1944, Serial No. 536,580, now Patent No. 2,472,612, dated June 7, 1949. Divided and this application May 24, 1945, Serial No. 595,587

3 Claims. (Cl. 13—25)

1

My invention relates to electric furnaces, the present application being a division of my co-pending application Serial Number 536,580, filed May 20, 1944, now Patent #2,472,612 issued on June 7, 1949.

The invention, which has among its objects the provision of an electric furnace which will be air tight and free from the deleterious effects of expansion of the furnace structure, will be best understood from the following description when read in the light of the accompanying drawings of an embodiment of the invention, the scope of which latter will be more particularly pointed out in the appended claims.

In the drawings:

Fig. 1 is a section on the line 1—1 of Fig. 2, with parts in elevation;

Figs. 2 and 3 are, respectively, sections on the lines 2—2 and 3—3 of Fig. 1, with parts in elevation;

Fig. 4 is a rear elevation of the furnace according to Figs. 1, 2 and 3;

Fig. 5 is an isometric view, with parts broken away, of the body portion or lining of the furnace chamber;

Fig. 6 is a section on the line 6—6 of Fig. 1 on an enlarged scale, with parts omitted;

Fig. 7 is a fragmentary elevation on an enlarged scale of parts shown by Fig. 4;

Fig. 8 is a section on the line 8—8 of Fig. 7; and Fig. 9 shows a detail.

Although many features of a furnace according to the invention are of general application, the furnace shown by the drawings is particularly applicable for use in the practice of the methods disclosed by applicant's co-pending application Serial Number 519,887, filed January 27, 1944, now Patent #2,429,584 issued on October 21, 1947. In such a furnace a molten copper base alloy containing zinc is treated under non-oxidizing conditions by heating it to a high temperature in the presence of carbonaceous material for removing its zinc content, the carbonaceous material constituting the lining or body portion of the furnace chamber containing the molten metal. When such a furnace is of large size it has been found necessary to build up this lining of carbon blocks, and, for insuring against entrance of air through the interstices of the furnace walls, to surround those walls with an imperforate metal casing which operatively tightly fits those walls, it being understood that entrance of air into the furnace chamber would not only make it impossible to treat the molten

2

metal under non-oxidizing conditions but also would destroy the carbonaceous lining by what amounts to combustion of the same. With a furnace so constructed extreme difficulty has been encountered in preventing the metal casing from overheating and from being ruptured by stresses imparted by expansion of the furnace walls when the latter are heated, it being understood that the interior of the furnace commonly will be at about 3200° F. and that the metal casing if heated in excess of about 350° F. will soften and lose its structural strength.

Referring to the drawings, the furnace illustrated comprises a lower portion 1 and a removable cover portion 3 (Figs. 2 and 4). The lower portion comprises a metal casing, preferably of mild steel, having the four lateral walls 5 and a bottom wall 7, the joints between these walls being welded together to form an integral air tight structure. As shown, the bottom of the casing is supported on the spaced I-beam supports 9 extending transversely of the casing. Also, as shown, the casing is reinforced by the vertical corner angle-irons 11 (Figs. 1 and 4) welded to the walls 5, between which angle-irons extend, at the front and rear of the furnace, the horizontal I-beams 13 welded thereto, spacing strips 14 being placed between the I-beams and casing and welded to each so that the I-beams as well as the angle-irons 11 are in substance integral with the casing. The end walls of the casing, as shown, are reinforced by the vertically extending I-beams 15 welded to those walls so as in substance to be integral therewith.

The cover of the furnace similarly comprises a metal casing, preferably of mild steel, having the top wall 17 and four lateral walls 19 (Figs. 2 and 3). The vertical corners between the lateral walls 19 are welded to each other and to the vertical bars 20, one of which latter is placed at each corner of the cover and extends from above the top wall 17 downward to intermediate the height of the lateral walls. The upper edge of each of the walls 19 and the corresponding edges of the top wall 17 throughout their lengths are welded to angle-iron reinforcing members 21, these members at each of opposite ends abutting with the bars 20 and being welded thereto. The cover portion of the casing, as shown, is further reinforced by the channel-irons 23 extending about the lateral walls 19 adjacent their upper edges, the channel-irons being welded to said walls and to the bars 20 with which latter their ends abut, and is still further reinforced by

the angle-irons 25 extending about the interior of this portion of the casing at the lower edges of the lateral walls 19, to which walls the angle-irons 25 are welded. As shown, adjacent the top of the lateral walls 5 of the lower portion of the casing and interiorly of those walls are angle-irons 27 extending entirely about the casing and welded thereto, the horizontal legs of the angle-irons 25 resting upon the horizontal legs of the angle-irons 27 when the cover of the furnace is placed on the lower portion of the furnace.

For making an air tight joint between the lateral walls 5 of the casing for the lower portion of the furnace and the lateral walls 19 of the casing for the cover portion of the furnace, the last mentioned walls have welded thereto horizontal I-beams 29 which extend for the full length of each side of the cover, the lower ends of the bars 20 abutting with the top edges of these I-beams at the corners of the cover and being welded thereto. Carried by these I-beams is a member extending entirely about the cover comprising the horizontal top plate 31 and spaced downwardly projecting vertical plates 33, the innermost of the latter being welded to the outer sides of the I-beams. Welded to the lateral walls 5 of the casing for the lower portion of the furnace are horizontal angle-irons 35 which extend entirely around the furnace. Carried by these angle-irons are horizontal plates 37 coextensive therewith, which plates 37 carry the spaced upwardly projecting plates 39 coextensive with said plates 37. When the cover is in position the plates 33 enter the spaces between the plates 39, which spaces may be filled with oil or sand, or a mixture of the two, so as to make an air tight labyrinth seal.

As best illustrated by Figs. 1, 2, 3 and 5, the body portion or lining of the furnace chamber has a bottom formed of massive blocks 41, of non-graphitic carbon, extending for the full width of the chamber. At one end of the furnace is a transverse block 43, of the same material, resting upon the upper surface of the adjacent bottom block 41, the block 43 also extending entirely across the furnace. As shown, the block 43 is provided above its lower surface with an opening 45 (Figs. 2 and 5) through which extends a conduit 47 for supplying molten metal to the furnace chamber. As shown, this conduit has a downwardly projecting spout 49 which extends into a hollow 51 of a cup-shaped block 53, the metal entering the furnace through the conduit 47 overflowing the rim of the block into the furnace chamber to fill the latter with molten metal to the level L (Figs. 2 and 3), while the hollow 51 of the block is kept filled with molten metal to seal the spout of the conduit so as to prevent entrance of air into the furnace chamber and to prevent escape of zinc or other fumes therefrom. As shown, the upper surface of the bottom of the lining is recessed at 55 and the adjacent portion of the inner surface of the block 53 is recessed at 57 (Fig. 5) to receive the block 53 to hold it in position. Conveniently the conduit 47 and block 53 are formed of graphite to facilitate machining of the same.

Molten metal may be discharged from the furnace chamber through a conduit 59, preferably formed of graphite, the bore of which conduit communicates with said chamber at the level of the upper surface of the blocks 41, as illustrated in Fig. 2, so that all the molten metal in the chamber may be drained therefrom when desired. The adjacent end wall portion of the fur-

nace chamber with which the molten metal contacts is constituted by a block 61, of non-graphitic carbon, which extends for the full width of the chamber, this block having an opening 62 through which the conduit 59 passes. To insure against leakage of metal about the exterior of the conduit it is necessary for it tightly to fit the opening in the furnace walls through which it passes, which assurance cannot be had if the block 61 should rest on the extreme top of the adjacent block 41 as does the block 43 at the opposite end of the furnace. Consequently the adjacent block 41 is downwardly recessed as shown at 63, while the block 61 is extended downward to fill said recess, thus enabling the walls of the opening 62 to be wholly constituted by the block 61. The upper portion of the transverse wall comprising the block 61 may be built up to the level of the top of the transverse block 43 by a block 65 of the same length as the block 61, the two preferably having a tongue and groove fit as indicated at 67 (Figs. 2 and 5). Normally the conduit 59 is closed by a removable screw-threaded graphite plug 69 which may be turned by a key wrench inserted through the exterior open end of the conduit, and to insure against leakage the portion of the conduit at the right of the plug, as viewed in Fig. 2, may be normally filled with fireclay and closed by a removable cap 71.

Zinc fumes and the like may be discharged from the furnace chamber through a suitable conduit 72, which in practice, when the furnace is used for treating zinciferous metal, leads to a closed zinc condenser.

As shown, the opposite longitudinal walls of the body portion or lining of the furnace chamber are constituted by blocks 73 extending for the full length of the chamber, the transverse blocks at the ends of the chamber being recessed as indicated at 75 (Figs. 1 and 5) for receiving the end portions of the blocks 73.

Preferably the carbon blocks constituting the body portion or lining of the furnace chamber are accurately machined to fit with each other, adjacent surfaces being formed with keyways 77 which receive elongated non-graphitic carbon keys 79 to lock the parts together. These keyways also act to prevent escape of molten metal from the furnace chamber should the same tend to leak through the joints between the blocks. For further insuring against such leakage the lateral walls of the chamber are surrounded by an integral layer 81 of carbonaceous material. This material may be applied in the form of a thick paste rammed into the space between the carbon blocks and the surrounding brickwork, a space several inches in width being left between the carbon blocks and the surrounding brickwork to permit entrance of the paste. This paste may be the material known as "green electrode paste" consisting of a mixture of comminuted carbon and coal tar, and being the material commonly employed for making molded carbon electrodes. After the furnace is in operation the paste will bake and form an integral layer of hard carbon. As shown, the exterior sides of the blocks 43 and 61 at the two extreme transverse sides of the carbon lining project slightly beyond the adjacent sides of the end blocks 41 forming the bottom of the lining so as to provide shoulders 83, which shoulders act to prevent any tendency of the layer 81 to move upward, that is to say, they act to lock the layer to the lining.

As shown in Figs. 2 and 3, the body portion or

lining of the furnace chamber rests upon a layer of solid graphite formed by lapped slabs 85, of several inches thickness, extending entirely across the bottom of the lining. Under the high temperature conditions at which the furnace is operated graphite has remarkably high lubricating or anti-friction properties, and permits the heavy furnace lining to expand freely on the brickwork which supports the lining on the bottom of the metal casing.

As illustrated in Fig. 1, surrounding the carbon layer 81 is a layer formed of the bricks 87 and slabs 89, while surrounding the slabs 89 is a layer of bricks 81, the space between the latter and the lateral walls 5 of the casing being filled by a layer of lagging 93. The bricks 87 and slabs 89 are preferably formed of highly refractory fireclay of high alumina content, preferably of the quality known as "60% alumina." This material will withstand and operate efficiently at temperatures up to about 3000° F. Consequently the lateral walls of the furnace lining should be of such thickness as to reduce the temperature at the exterior of the carbon layer 81 to at least such value. For furnaces in which the hottest portions thereof, namely, the portions below the resistors hereinafter referred to, are at about 3200° F. this will mean a thickness of the blocks constituting the carbon lining of about 18 inches, and a thickness of about 12 inches above those portions where the furnace is not quite as hot. It however will be understood that where lower temperatures are employed the lining need not be as thick, while if firebricks which are less heat refractory are employed the lining must be thicker for a given furnace temperature than would otherwise be necessary. The carbon lining, although extremely heat refractory, is a relatively poor heat insulator, while the material described for the layers 87 and 89, although not as heat refractory, is a better heat insulating material. Hence, by employing the layers 87 and 89, not only may the carbon walls be made thinner, but the overall thickness of those walls and the layers 87 and 89 may be made thinner than if that overall thickness were constituted by walls of carbon.

The bricks of the layer 81 which surrounds the layers 87 and 89 are preferably common insulating firebricks which, although having better heat insulating properties than the material of the layers 87 and 89, are less heat refractory. Consequently the total thickness of the layers 87 and 89 should be such as to reduce the temperature applied to the layer 81 to that which the bricks constituting the latter will withstand and at which they will operate most efficiently as a heat insulating layer, say a temperature not exceeding 2300° F. Where, for example, the internal temperature of the furnace is about 3200° F. and the carbon lining is of the specific thickness above mentioned, satisfactory results will be secured when the total thickness of the layers 87 and 89 is about 6½ inches.

The heat refractory lagging 93 employed is resiliently yieldable, so as to permit the interior furnace structure to expand and contract horizontally on the antifriction layer 85 without injury to the metal casing of the furnace. This lagging material is preferably prefabricated slabs of porous fibrous silicious diatomaceous material such as the material sold under the name "Insulag." It resembles ordinary sheet magnesia lagging, which latter material in fact can be substituted for it where much lower temperature

conditions are employed. The material will withstand and operate efficiently at temperatures not exceeding about 1800° F., and the thickness of the layer 93 is therefore such as to reduce the temperature applied to the lagging to one not exceeding that value. In the example given in the preceding paragraphs satisfactory results will be secured when the thickness of the layer 93 is about 4½ inches. The thickness of the lagging should be such as to reduce the temperature applied to the metal casing to one that will not cause overheating of the metal and at the same time will permit the internal furnace structure to expand without injury to the casing. Ordinarily under the temperature conditions mentioned the lagging may be about 1 inch thick, and such thickness will take care of the expansion of furnaces up to about 15 feet long or wide.

The brickwork below the bottom of the furnace lining may consist of an outer layer 95 of firebrick of the same material as the bricks of the layer 81 about the lateral walls of the lining, and, between the layer 85 and the carbon slabs or plates 85, a further layer 97 of firebrick of the same material as the layers 87 and 89.

As shown, the carbon blocks 43, 61 and 73 forming the lateral walls of the furnace chamber are formed to provide a shelf 98 adjacent their tops, upon which shelf rest plates 99, preferably of graphite, extending entirely across the furnace chamber. Upon these plates rests a body 101 of refractory insulating material, preferably broken charcoal. When electric current is passed through the resistors hereinafter described the same are heated to incandescence. The plates 99 above the resistors become incandescent as well as the interior walls of the carbon blocks, the plates 99 and the resistors acting to reflect heat downward on the surface of the metal being treated.

As shown, the cover of the furnace comprises a flat arch comprising the superimposed wedge-shaped blocks 103 (Fig. 3) extending lengthwise of the cover at opposite sides thereof, and the wedge-shaped blocks 105 (Fig. 2) extending transversely of the cover at opposite ends thereof, these blocks resting upon the horizontal webs of the angle-irons 25 and abutting with the lateral walls 19 of the metallic casing of the cover. Extending transversely across the furnace and supported by the wedge-shaped blocks are blocks 107 of non-graphitic carbon. Resting upon these blocks is a layer 109 of refractory heat insulating firebrick, and between the latter and the top wall 55 of the casing for the cover is a layer 111, preferably of insulating silicious cementitious material. As shown, the blocks 107 are formed with a recess 113 of V-shaped cross-section as viewed in Fig. 3. In building the furnace the relatively finely broken up mass 101 of charcoal is distributed on the plates 99 in amount just about sufficient to fill the recess 113, care being taken not to have an excess amount so that when the cover is put in position it, owing to its great weight which in a furnace of the size hereinafter mentioned will be in the order of 14 tons, will not exert such pressure on the plates 99 as will break them. The lug bars 28 hereinbefore referred to are preferably provided with perforations 114 for adapting the cover to be attached to a crane hoist so that it may be removed and replaced.

The longitudinally extending carbon blocks 73 of the furnace lining, as shown, are further formed to provide shelves 117. These shelves

serve to support the bar-like resistors 119, which latter are preferably formed of graphite. For a furnace chamber, which at its bottom is about 9 feet long and 4 feet wide holding about 5 tons of metal when the pool of the latter is about 6 inches deep, these resistors may be about 6 inches in diameter spaced about 16 or 17 inches apart.

As shown, the ends of the resistors are connected for series flow of current by plates 121, preferably of graphite, these plates being supported on the shelves 117 by blocks 122 of heat refractory electric insulating material such as sintered aluminum oxide Al_2O_3 of high purity, say about 99.5%, the ends of the resistors being screw-threaded, as shown in Fig. 1, and secured to the plates by graphite clamping nuts 123. As shown in Figs. 1 and 6, the openings 125 in the plates 121 through which the resistors extend are elongated lengthwise of the plates so that the resistors, although securely clamped thereto by the nuts 123, may slide longitudinally of the plates to permit expansion and contraction of the series of resistors longitudinally of the furnace particularly when the walls of the latter expand and contract, it being understood that graphite has high lubricating or anti-friction qualities when heated to incandescence. As shown, the ends of the resistors are secured by means of graphite coupling sleeves 127 to larger diameter graphite extensions 129 projecting through openings 131 in the adjacent carbon block 73 in spaced relation to the walls of such opening. In alignment with the openings 131 the furnace walls and casing are formed with openings through which the enlarged diameter portions 130 of the resistor extensions 129 lead to the exterior of the furnace, the openings through the brickwork, as shown, being constituted by the bores of sleeves 133 (Fig. 1), which sleeves are of heat refractory electric insulating material preferably alundum. As shown, the space between the walls of each sleeve and associated extension is packed with a yieldable layer 135 of asbestos or other yieldable heat refractory material, so that the extension despite the packing remains operatively in spaced relation to the surrounding walls of the sleeve in the sense that relative movement between them transversely of the extension is not prevented.

As best illustrated in Fig. 8, screw-threaded on the enlarged diameter end portion 130 of each resistor extension 129 is the base 137 of a terminal 139, preferably formed of copper, the base being insulated from the walls of the metallic furnace casing by a washer 141 of yieldable refractory insulating material such as asbestos. As shown, the base 137 is provided with the radial water passages 142 with which communicate the water supply passage 143 and water discharge passage 144 leading to the end of the terminal for connection to suitable hoses. The water circulated through the base and terminals keeps them and the adjacent portions of the resistor extensions 129 cool. Because of the cooling water and the increased diameter of the resistor extensions as compared to the diameters of the heating resistors, although the latter are heated to incandescence the terminals and adjacent portions of the extensions, including the portions of the latter within the sleeves 133, are kept relatively cool.

As shown, each terminal 139 extends through an opening 145 in a plate 146 of insulating material, to which plate the base portion 137 of the terminal is clamped by a nut 148 screw-

threaded on the terminal. This plate, as shown, is relatively thick, say about 1 inch, so as to give it considerable strength. Preferably the material of the plate is one of those used for panels of radio instruments as, for example, material sold under the name "Micarta." Surrounding the base of the material is shown a sleeve 147 which is stiffly flexible transversely of its axis but non-extensible. This sleeve in detail may have the construction shown by Fig. 9, that is to say, may have the interlocked spirally wound portions 149 which are packed with asbestos or the like, as indicated at 151, to render the sleeve air tight. At its outer end the sleeve, as shown, is welded at 153 to a metal ring 155 which is secured to the plate 146 by bolts 157, a packing 159, preferably of asbestos, being placed between the ring and the plate for rendering the joint between them air tight. At its opposite end the sleeve, as shown, is welded at 161 to a metal ring 163 which is secured to the metal furnace casing, preferably by welding as shown at 165.

The sleeves 147 in conjunction with the packings 135 insure against entrance of air into the furnace chamber through the openings in the furnace wall through which the resistor extensions 129 pass. At the same time the sleeves being laterally yieldable prevent undue stresses being imparted to the resistor extensions when the metal casing of the furnace expands, and likewise permits the resistor extensions to move relative to the casing in so far as they tend to so move by reason of relative expansion between the metal casing and the walls of the furnace interiorly of the casing.

For supporting the terminals 139 and the resistor extensions against the stresses of the cables connected to the terminals, in the embodiment of the invention shown the two insulating plates 146 are connected to the opposite ends, respectively, of a bar 167, which latter is rigidly supported by posts 169 (Fig. 4) carried by a plate 171 (Fig. 3) secured to the projecting ends of the I-beam supports 9 for the furnace. As shown, metal plates 173 are welded at 175 to the ends of the bar 167, while the insulating plates 146 are secured to these metal plates by bolts 177, the perforations 179 in the plates 173 through which the bolts pass being elongated in the direction of the fixed bar 167 so as to permit relative movement longitudinally of the furnace between the plates 145 and that bar.

The current employed for energizing the resistors commonly will be in the order of 6,000 to 10,000 amperes, and when this is an alternating current a very strong alternating electro-magnetic field is set up about the terminals and resistor extensions 129. It has been found that this field is sufficient seriously to overheat the portions of the casing walls adjacent the resistor extensions when the casing is of steel because of the hysteresis phenomena involved. To avoid this effect, in the present embodiment of the invention the portion of the lateral walls 5 of the casing adjacent each resistor extension is constituted by an insert 181 of non-magnetic material, preferably silicon bronze which has a tensile strength in the order of steel. As shown, each insert is of the same thickness as the rest of the lateral walls 50 of the casing and is secured thereto by a metal frame 183 welded to the insert and the lateral walls 5. As shown, the inserts extend farther from the terminals toward the center of the length of the furnace than toward the ends of the furnace 75 because the electro-magnetic field is strongest be-

tween the two terminals. When an alternating current is employed, also the bar 167 preferably is provided with an insert 185 of non-magnetic material, such as copper or silicon bronze, for breaking the magnetic path between the regions adjacent the terminals, as otherwise the bar 167 is liable to overheat and weaken. Likewise the metal of the sleeve 147 and the rings 155 and 163 associated with said sleeve are preferably of non-magnetic material, such as bronze, to prevent their overheating when an alternating current is employed.

It will be understood that within the scope of the appended claims wide deviations may be made from the form of the invention described without departing from the spirit of the invention.

I claim:

1. An electric furnace having, in combination, built up walls forming a furnace chamber, an outer metallic casing surrounding said walls for supporting them and rendering them air tight, heating means in said chamber comprising a row of rigid heating resistors connected together by rigid end members, a rigid resistor extension at each end of said row extending through aligned openings formed in said walls and casing in operatively laterally spaced relation to the walls of said openings to the exterior of said casing, air tight laterally flexible metallic sleeves carried by said casing at the exterior thereof, which sleeves receive the portions of said resistor extensions at the exterior of said casing in laterally spaced relation to said portions, the end of each sleeve adjacent the casing having an air tight connection thereto, and means including an electric insulator adjacent the opposite end of said sleeve connecting that end in air tight insulated relation to said portion of said resistor extension received by the sleeve.

2. An electric furnace having, in combination, built up walls forming a furnace chamber, an outer metallic casing surrounding said walls for supporting them and rendering them air tight, heating means in said chamber comprising a row of rigid heating resistors connected together by rigid end members, a rigid resistor extension at each end of said row extending through aligned openings formed in said walls and casing in operatively laterally spaced relation to the walls of said openings to the exterior of said casing, air tight laterally flexible metallic sleeves carried by said casing at the exterior thereof, which sleeves receive the portions of said resistor extensions at the exterior of said casing in laterally spaced relation to said portions, the end of each sleeve adjacent the casing having an air tight connection thereto; and means including a terminal carried by each of said portions of said extensions and an electric insulator adjacent the end of each sleeve remote from the casing, through which insulator such terminal projects, for securing that end of the

sleeve in insulated air tight relation to said portion of said extension.

3. An electric furnace having, in combination, built up walls forming a furnace chamber, an outer metallic casing surrounding said walls for supporting them and rendering them air tight, heating means in said chamber comprising a row of rigid heating resistors connected together by rigid end members, a rigid resistor extension at each end of said row extending through aligned openings formed in said walls and casing in operatively laterally spaced relation to the walls of said openings to the exterior of said casing, air tight laterally flexible metallic sleeves carried by said casing at the exterior thereof, which sleeves receive the portions of said resistor extensions at the exterior of said casing in laterally spaced relation to said portions, the end of each sleeve adjacent the casing having an air tight connection thereto, a terminal carried by each of said portions of said extensions, which terminals have base portions received by said sleeves in laterally spaced relation thereto, and electric insulators carried by the ends of the sleeves remote from the casing in air tight relation thereto, which insulators are formed with openings through which said terminals project in fluid tight relation thereto.
